CONTROL MEANS FOR REFRIGERATING APPARATUS

Frederick Hyde Hibberd, Harrison, N. Y., assignor to Ingersoll-Rand Company, Jersey City, N. J., a corporation of New Jersey

Application November 16, 1937, Serial No. 174,774

3 Claims.

(Cl. 62—2)

The invention relates to refrigerating apparatus wherein the temperature conditions, under which the apparatus is operating, control the operation of the apparatus. It relates more particularly to the type of refrigerating apparatus wherein evacuating means remove vapor from an evaporator and discharges it into a condensing means which is cooled by fluid medium. Accordingly, an object of the invention is to control the operation of the evacuating means by the temperature of the fluid medium in the condensing means.

Another object is to prevent waste of the power used for refrigerating purposes.

Other objects will be in part obvious and in part pointed out hereinafter.

The accompanying drawing shows diagrammatically, an elevation, partly in section, of refrigerating apparatus and control means therefor constructed in accordance with the principles of the invention.

Referring to the drawing, the invention comprises an evaporator tank 1 such as is commonly employed in refrigerating apparatus consisting of two or more vaporization chambers 3. Outlet pipes 5 lead from the vaporization chambers (two of which are shown here) and carry the chilled refrigerant to the point where the refrigeration is required. An inlet pipe 7 returns the warmed refrigerant to the chambers of the evaporator.

Separate evacuators 9 and 11 are provided for each chamber in the evaporator.

The evacuators are of standard construction and are operated by steam supplied through the pipes 13 and 15. These pipes connect with a common header 17 and are controlled by valves 19 and 21. The evacuators remove the vapor from the evaporator and discharge it into a condenser 23 which may be of any standard construction, using a liquid cooling medium such as water.

The condenser 23 is supplied with cooled water through a cooling water circuit consisting of a conduit 25 leading to an open cooling tower 27. Water is removed from the bottom of the cooling tower through the pipe 29 by the pump 31 and is returned to the condenser by the header 33.

The structure thus far described is a conventional type of refrigerating apparatus which operates satisfactorily for the most part. Occasionally, however, when the refrigerating load is heavy, the evacuators will discharge so much hot vapor into the condenser that the cooling water will be unable to remove all the heat. In other words, the temperature of the cooling

water becomes so high before it leaves the condenser that the cooling tower is unable to cool it sufficiently before it is returned to the condenser. When this occurs, the vapor in the condenser will not be condensed and a rise in temperature with a corresponding increase in pressure will occur. Such conditions in the condenser will cause the load to "surge" in the evacuators or "break back" through the evacuators, suspending refrigeration with the accompanying losses of power and refrigerating effect. In order to prevent such conditions from occurring it is proposed to control the operation of the evacuator 11 in accordance with the temperatures of the condenser cooling water.

In the form illustrated a thermostat 35 is provided in the pipe 29 leading from the bottom of the air cooler to the pump. This thermostat is connected to a valve 37 and controls the action of this valve.

In the operation of the apparatus, the evacuators 9 and 11 remove the vapor from the chambers 3 in order that the refrigerant in the chambers may be chilled. The vapor is discharged into the condenser 23 and the chilled refrigerant is removed from the evaporator by pipes 5 and then returned to the chambers by pipes 7.

Under normal operating conditions, the refrigerant is returned to the evaporator 1 at a temperature high enough to prevent the evacuators 9 and 11 from lowering the temperature in the evaporator chambers to the freezing temperatures and low enough that the heat load on the condenser 23 is such that the condensing water is sufficiently cooled by the water tower 27 that it returns to the condenser 23 at a temperature low enough to prevent surging of the load on the evacuators 9 and 11 since all the vapors discharged into the condenser 23 are condensed. Under such conditions the thermostat 35 will maintain the valve 37 open.

However, if the volume of vapor discharged into the condenser increases, the temperature of the cooling water leaving the condenser increases. As the temperature increases, the temperature of the cooling water returned to the condenser is correspondingly higher and not all of the vapor introduced into the condenser will be condensed so that vapor will accumulate in the condenser which, with the increase in temperature causing an increase in pressure, will greatly increase the pressure against which the evacuators discharge.

With present arrangement, however, when this occurs the increase of temperature of the cooling

water will actuate the thermostat causing it to close the valve 37 and thereby shut off the power supply to the evacuator 11. Thus the evacuator 11 may be shut down or intermittently operated 5 in order to reduce the heat load on the condenser and prevent condenser pressure from exceeding the point at which surging of the load would occur. Without some means of shutting off the load on the condenser the conditions would get 10 progressively worse until the apparatus would cease to function.

In this manner some of the evacuators may be kept in operation to maintain refrigeration and at the same time steam power will be saved. Thus, 15 absolute break of the refrigeration may be prevented.

It will be understood that the foregoing disclosure is illustrative only and that the invention is not limited to the control of one evacuator or 20 to systems embodying two evacuators.

I claim:

1. In a refrigerating apparatus, a multichamber evaporator, a steam evacuator for each chamber of the evaporator, a steam supply conduit for 25 the evacuators, branch conduits connecting each evacuator to the steam supply conduit, a water cooled condenser to receive the discharge of the evacuators, an outlet conduit to remove cooling water from the condenser, a cooling tower to receive and cool the condenser cooling water discharged by said outlet conduit, a cooling tower water outlet conduit to remove cooling water from the cooling tower and discharge it to the condenser, a thermostatically operated valve in one of 30 said branch conduits, and a thermostat in said cooling tower outlet conduit to operate the valve to control the flow of steam to the respective evacuator in accordance with the temperature of the condenser cooling water leaving the cooling 35 tower.

2. In a refrigerating apparatus, a multi-chamber evaporator, a steam evacuator for each chamber 40

of the evaporator, a steam supply conduit for the evacuators, branch conduits connecting each evacuator to the steam supply conduit, a water cooled condenser to receive the discharge of the evacuators, an outlet conduit to remove cooling water from the condenser, a cooling tower to receive and cool the condenser cooling water discharged by said outlet conduit, a cooling tower water outlet conduit from said cooling tower to said condenser, a pump interposed in said cooling tower outlet conduit to discharge cooling water from the cooling tower to said condenser, a thermostatically operated valve in one of said branch pipes, and a thermostat in said cooling tower outlet conduit to actuate said thermostatically operated valve to control the flow of steam to the respective evacuator.

3. In a refrigerating apparatus, a multi-chamber evaporator, a steam evacuator for each chamber of the evaporator, a steam supply conduit for 20 the evacuators, branch conduits connecting each evacuator to the steam supply conduit, a water cooled condenser to receive the discharge of the evacuators, an outlet conduit to remove cooling water from the condenser, a cooling tower to receive and cool the condenser cooling water discharged by said outlet conduit, a cooling tower water outlet conduit from said cooling tower to said condenser, a pump interposed in said cooling tower outlet conduit to remove cooling water from 25 the tower to the condenser, a manually operated valve in each said branch conduit to control the flow of steam therethrough, a thermostatically operated valve to control the flow of steam in one branch pipe, and a thermostat in said cooling 30 tower water outlet conduit to actuate said thermostatically operated valve whereby the flow of steam in said branch pipe to its respective evacuator is controlled in accordance with the temperature of the condenser cooling water leaving the 35 cooling tower.

FREDERICK HYDE HIBBERD.
